Des. 241,544
Patented Sept. 21, 1976

241,544

NOZZLE FOR AN AIR LINE

David Anthony Whitbread, Luton, England, assignor to
F. Brauer Limited, Harpenden, England

Filed May 20, 1974, Ser. No. 471,195

Term of patent 14 years

Int. Cl. D23—01

U.S. Cl. D23—34

FIG. 1

FIG. 2

FIG. 3

FIG. 4

FIG. 1 is a front end view of a nozzle for an air line embodying my new design;

FIG. 2 is a side view thereof;

FIG. 3 is a rear end view thereof; and

FIG. 4 is a fragmentary cross sectional view taken on line 4—4 of FIG. 3.

I claim:

The ornamental design for a nozzle for an air line, as shown.
